UNITED STATES PATENT OFFICE.

WALTER H. HUTH, OF CHICAGO, ILLINOIS.

AUTOMATICALLY REVERSIBLE MECHANICAL TOY.

1,388,113.

Specification of Letters Patent. Patented Aug. 16, 1921.

Application filed June 21, 1920, Serial No. 390,355. Renewed July 15, 1921. Serial No. 485,022.

To all whom it may concern:

Be it known that I, WALTER H. HUTH, a citizen of the United States of America, and a resident of Chicago, Illinois, have invented 5 a certain new and useful Improvement in Automatically Reversible Mechanical Toys, of which the following is a specification.

This invention relates to mechanical toys of that class in which means are provided 10 for automatically reversing the direction of travel when the toy encounters an obstruction.

Generally stated, the object of the invention is to provide an improved construction 15 and arrangement whereby a movable weight is arranged to shift forward or backward, depending upon whether the toy is traveling forward or backward, whenever the toy is stopped by an obstruction, and in which 20 there are means controlled by said weight to automatically reverse the direction of travel.

Another object is to provide an automatically reversible toy of this character having 25 provisions to insure a substantial momentary hesitation of the toy in stationary position before the reversal of travel takes place, so that the toy will travel until it strikes the 30 obstruction, then remain stationary for a short period of time, and then start back in the opposite direction.

Another object is to provide means to automatically produce a signal by the reversal 35 of the toy, the signaling device being operated during the hesitation of the toy or while it is standing still before the reversal 40 of movement takes place.

It is also an object to provide certain details and features of construction and combinations tending to increase the general 45 efficiency and the desirability of an automatically reversible mechanical toy of this particular construction.

To these and other useful ends the invention 50 consists in matters hereinafter set forth and claimed and shown in the accompanying drawings, in which—

Figure 1 is a plan of a toy ferry boat having propelling and reversing and signaling 55 means embodying the principles of the invention, showing the body or cabin portion of said boat removed.

Fig. 2 is a side elevation of said boat

showing the said body or cabin in dotted lines.

55

Fig. 3 is a plan of the motor and general mechanism of the boat.

Fig. 4 is a side elevation of the same.

Fig. 5 is a longitudinal vertical section on line 5—5 in Fig. 3.

60

Fig. 6 is a bottom plan of the structure shown in Figs. 3, 4, and 5.

Fig. 7 is a perspective of the device for ringing the bell which constitutes the audible signal which is produced by the reversal 65 of travel.

Fig. 8 is an enlarged section on line 8—8 in Fig. 5.

Fig. 9 is an enlarged section on line 9—9 in Fig. 6.

70

Fig. 10 is a detail sectional view of the governor.

Fig. 11 is an end elevation of the structure shown in Figs. 3, 4, and 5.

Fig. 12 is a vertical section on line 12—12 in Fig. 5.

Fig. 13 is an enlarged section on line 13—13 in Fig. 4.

Fig. 14 is a detail section on line 14—14 in Fig. 13.

80

Fig. 15 is a detail section on line 15—15 in Fig. 13.

As thus illustrated, the invention comprises a body 1 mounted on wheels 2 and 3, the latter having a driving axle or shaft 4 85 extending transversely of the toy. The body or cabin 5 may be of any suitable character. In the drawings the toy takes the general form of a ferry boat, but it will be understood that the invention may be embodied in a toy of any suitable form or character.

The body frame 6 of the motor and general mechanism of the toy is suitably secured upon the top of the platform or body 90 1, and has a spring barrel 7 at one side thereof to furnish the power for driving the toy, and a bell 8 at the other side.

The said spring barrel is connected by gear wheels 9, 10, 11, 12, and 13 with the pinion 14, and the latter engages and rotates the 95

pinion 15, all of these gears and pinions being suitably mounted on the body frame of the motor.

The pinion 14 engages a gear wheel 16 mounted on the body frame of the motor, while the pinion 15 engages a similar 100

gear wheel 17 mounted on the body frame, 105

an endwise movable shaft or journal 18 extending through the sleeves 19 upon which said gear wheels are mounted to rotate. This shaft or journal 18 has a gear wheel 20 mounted thereon and provided at opposite sides with means to engage the inner ends of the sleeves 19, so that the axle or journal 18 will be rotated by either one of the two gear wheels 16 and 17, which latter are driven 10 constantly in opposite directions while the toy is in operation. For this purpose it will be understood that the side of the gear wheel 16 may be provided with a lug 21 to engage one of the lugs 22 of the gear wheel 20, 15 while the gear wheel 17 is provided with a similar lug 23 to engage one of the lugs 22 of the shifting gear wheel 20, whereby a reversible clutch mechanism is provided. The gear wheel 20 has sliding engagement with 20 the wide pinion 24 which engages the gear wheel 25, whereby the latter is driven first in one direction and then in the other, by the reversal of the pinion 24, in a manner that will be readily understood. This gear 25 wheel 25 is mounted on a screw 26 which is fixed to the axle or shaft 4 previously mentioned, and clutch shoulders 27 are disposed at the ends of the screw 26 to engage the opposite sides of the gear wheel 25, to interlock the screw and gear wheel, so that rotation of the latter will rotate the said shaft or axle 4 which operates the propelling wheels 3 of the toy. Thus the gear wheel 25 is rotated first in one direction and then 30 in the other on the screw 26, with the result that the gear wheel is caused to shift laterally back and forth on the screw, and to engage first one shoulder 27 and then the other, thus rotating the screw and the axle 4 to 35 drive the toy. It will be seen, however, that the endwise shifting of the axle or journal 18 is not accompanied by an immediate reversal of the direction of travel, inasmuch as it takes some time for the gear wheel 25 40 to travel from one end of the screw 26 to the other end thereof, so that a substantial momentary hesitation of the toy is insured before the reversal of travel takes place.

Preferably, a signal is produced during 50 the hesitation of the toy, or while it is standing still, after encountering an obstruction, as will hereafter more fully appear; and, as shown, this signal comprises the said bell 8 and the striker 28 which is mounted on the 55 rock shaft 29 that extends through the sides of the body frame 6, and which is provided with a depending portion 30 for engagement with the element 31, which latter is pivoted on the bottom of the arm 32, the latter having end portions 33 which engage the opposite sides of the gear wheel 20 previously 60 mentioned. The arm 32 is pivoted on the bottom of the body frame at 34, and the pointed element 31 has a stop 35 to limit its 65 oscillation. A spring 36 is arranged to pull

the striker 28 against the bell. When the arm 32 swings in either direction, the element 31 engages the depending portion 30, and thereby rocks the shaft 29, causing the striker 28 to move away from the bell, and as soon as the portion 30 is disengaged by the element 31, the spring 36 then pulls the striker back against the bell, thus producing the signal. In this way, therefore, the audible signal is produced by the lateral shifting of the gear wheel 20, and during the hesitation of the toy in stationary position before the reversal of travel takes place.

The shifting of the axle or journal 18 is automatic, and is accomplished by means of 80 the two cams 37 and 38, one cam pushing the axle endwise in one direction, and the other cam pushing it in the opposite direction. These two cams are mounted on the sides or arms 39 of the weight 40, which latter is 85 pivoted at 41 near the bottom of the motor body and arranged to be tilted forward and backward by momentum—that is to say, the said weight will swing over by momentum when the toy is stopped suddenly by an ob- 90 struction.

With this construction, therefore, the toy can be wound up and started in one direction, and as soon as it runs into something or is stopped, the momentum will carry the 95 weight 40 forward a distance, thus shifting the axle or journal 18 and thereby operating the reversing mechanism. The reversal of travel, however, does not take place immediately, as previously explained, but 100 does occur as soon as the gear wheel 20 has rotated sufficiently on the screw 26 to shift it into engagement with one of the clutch shoulders 27, and during this interval of time the signal is produced. Then the toy 105 starts back in the opposite direction, and can be reversed again by stopping it suddenly, inasmuch as the weight 40 will swing in the opposite direction and again reverse the transmission of power to the wheels by 110 which the toy is propelled along the floor.

The governor 42 is mounted in any suitable position adjacent to the gearing to be rotated thereby, and will expand by centrifugal force against the tension of the 115 springs 43, to cause the weights 44 to engage the stationary cylinder 45, thus frictionally retarding the movement and preventing the motor from running too fast.

What I claim as my invention is:—

1. In a reversible mechanical toy, the combination of a motor, propelling means, transmission gearing between the motor and said propelling means, a weight mounted on the toy to move forward and backward by 125 momentum, when the toy is stopped, and devices operated by said weight to control said gearing and thereby reverse the direction of travel.
2. A structure as specified in claim 1, said 130

gearing having provisions to insure a substantial hesitation of the toy in stationary position before the reversal of travel takes place.

5 3. A structure as specified in claim 1, said gearing having provisions to insure a substantial hesitation before the reversal of movement, and means operated by said motor to produce a signal during this hesitation of the toy.

10 4. A structure as specified in claim 1, said weight being pivoted to tilt back and forth about a transverse axis below the center of gravity thereof, so that sudden stoppage of the toy throws the weight one way or the other, depending upon which way the toy is traveling.

15 5. A structure as specified in claim 1, said devices comprising a transverse shaft having a reversible clutch mechanism thereon, and cams operated by said weight to shift said shaft endwise to reverse the drive.

20 6. A structure as specified in claim 1, in combination with a sound-producing device, and means whereby said sound-producing device is operated by said motor after the toy stops and before it starts in the opposite direction.

25 7. A structure as specified in claim 1, in combination with means operated by said devices to automatically produce a signal by the reversal of the toy.

30 8. A structure as specified in claim 1, said transmission gearing having a screw, a gear wheel mounted to rotate on said screw and shift back and forth laterally thereon, and means whereby said gear wheel becomes locked to the screw after shifting laterally a distance in either direction, thereby to insure a substantial momentary hesitation

of the toy before the reversal of travel takes place.

35 9. A structure as specified in claim 1, said transmission gearing having a screw, a gear wheel mounted to rotate on said screw and shaft back and forth laterally thereon, means whereby said gear wheel becomes locked to the screw after shifting laterally a distance in either direction, thereby to insure a substantial momentary hesitation of the toy before the reversal of travel takes place, and a signal device operated by the lateral movement of said gear wheel.

40 10. In an automatically reversible mechanical toy, a reversing mechanism comprising a screw, a gear wheel mounted to rotate on said screw and shift laterally back and forth thereon, and means whereby said gear wheel becomes locked to the screw after shifting laterally a distance in either direction, thereby to insure a substantial momentary hesitation of the toy before the reversal of travel takes place.

45 11. A structure as specified in claim 10, in combination with a signal device operated by the lateral movement of said gear wheel.

50 12. In an automatically reversible mechanical toy, having a reversing clutch device, a reversing mechanism comprising a rotary screw for slowly opening and closing said clutch device, means to transmit power through the clutch to propel the toy in either direction, means to automatically control said clutch to reverse the direction of travel of the toy, and means whereby the slow action of the clutch serves to insure a substantial hesitation of the toy before the reversal of travel takes place.

55 WALTER H. HUTH.
